UNITED STATES PATENT OFFICE.

ALBERT C. SCHMIDT, OF PHILADELPHIA, PENNSYLVANIA.

DESIGN FOR A BADGE.

SPECIFICATION forming part of Design No. 15,609, dated December 9, 1884.

Application filed August 16, 1884. Term of patent 7 years.

To all whom it may concern:

Be it known that I, ALBERT C. SCHMIDT, a citizen of the United States, residing at Philadelphia, in the county of Philadelphia and State of Pennsylvania, have invented certain new and useful Designs for Badges; and I do declare the following to be a full, clear, and exact description of the invention, such as will enable others skilled in the art to which it appertains to make and use the same, reference being had to the accompanying drawing, and to letters or figures of reference marked thereon, which forms a part of this specification.

15 The figure of the drawing is a representation of the badge.

This design consists in the shape and ornamentation of a badge, as hereinafter shown and described. The main outline is in banner form, the top surmounted by scroll-work. In a field in the middle portion of the top of the banner is shown a cross and crown. In a triangular field in the upper corner on the left is shown a book. In a triangular field in the upper corner on the right is shown a skull. At the middle of the bottom portion of the banner is represented a shield. The middle

portion or main portion of the banner is occupied by a field having thereon an eagle represented with outspread wings and as clasping two swords. Across the upper portion of the field, above the eagle, are ribbon or scroll form spaces.

Having described this design, I claim—

The design for a badge herein described 35 and shown, being in outline of banner form, having its main or middle portion occupied by a field in which is represented an eagle with outspread wings and clasping two swords, above the eagle a crown, beneath the eagle a 40 shield, at the upper right-hand corner of the banner a triangular portion with a representation of a skull, at the left-hand corner a triangular field with a representation of an open book, and at the upper edge of the banner 45 ribbon or scroll form spaces.

In testimony that I claim the above I have hereunto subscribed my name in the presence of two witnesses.

ALBERT C. SCHMIDT.
